OF D 603

WAIRNICK & LEIBRANDT

ASSIGNEES of

G. SMITH & H. BROWN.

DESIGN for STOVE called the
N° 603 "PENN RADIATOR."

Patented Oct. 24, 1853.

Fig. 2

2 of 2

Fig. 4.

Fig. 3.

Garrettson Smith & Henry Brown,
of Philadelphia, Pa.

Assignors to

C. W. Warnick & F. Leibrandt of same place.
Letters Patent No. 603. Dated Oct. 14th, 1853.

The schedule referred to in these Letters Patent, and making part of the same is as follows:

To all whom it may concern:

Be it known, that we, Garrettson Smith & Henry Brown of the City and County of Philadelphia, and State of Pennsylvania, have produced a new and original design in stoves called the

"Penn Radiator,"

and we do hereby declare that the following is a full, clear, and exact description of the same, reference being had to the annexed drawings forming part of this specification, in which

Figure 1 is a front elevation of the stove,

Figure 2 is a plan of the top plate,

Figure 3 is a plan of the base plate,

Figure 4 is a front elevation of the foot.

In the several figures, similar letters indicate the same part of the stove's design.

Symmetrical designs have but one half of their details shown.

The front plate A has at top a concave a, ornamented in bas-relief by the festoons b, and drops c and c'. Below the concave a, is the moulding d, beneath which are the festoons e and drops h and h'. On each side of the plate are the sunken panels f f' f'', bearing the ornaments g g' g'' in bas-relief. In the middle of the plate, is the feed door c, and sunken panel B, the latter bearing two small panels i, with ornaments in bas-relief similar to g and g'. The outer edge of the panel is surrounded with the projections l. The feed door c is surrounded with the moulding K, and has in its panels the opening m, m' m''. Around its outer edge are the projections l'. The lower moulding D bears the projections o. The details of the above described design of the front plate are fully set forth in figure 1.

The base plate B is of the form shown in figure 3, its edge being made up

Dec. 603

of the mouldings n n n", ornamented in bas-relief by the figures p p p". Upon the hearth is the inscription
"Penn Radiator, 1853, patented."

in raised capitals and numerals; and surrounding the ash hole covering, are the ornaments q q. The configuration and arrangement of the several ornaments and mouldings on this plate are represented fully in figures 1 and 3.

The top plate G is in form as shown in figure 2, its edge embellished by the moulding H, made up as shown in figure 1. The plate is ornamented in bas-relief and with the figures r r r", and foliage s, arranged as seen in figure 2, and bears the inscription

"Warnick & Leibrandt, Philadelphia."

in raised capitals. The particular configuration of ornaments, mouldings, and inscriptions is fully set forth in figures 1 and 2.

The foot R is of the form shown in figures 1 and 4, and is embellished with the foliage t and t', sweeps u and u', elliptical projections w, and otherwise ornamented as set forth in the above mentioned figures.

The stove is surmounted with the urn V, which is circular, and of the form represented in figure 1. The base T is ornamented by the mouldings a' and figures a", b' b", in bas-relief. The bowl S, is embellished by the figures x x' in bas-relief. The cover P has the openings z for the escape of steam, is surmounted with the foliage y, and otherwise ornamented as shown in the drawing, the details of the configuration and arrangement of ornament being as set forth in figure 1.

What we claim as our production, and desire to secure by Letters Patent, is

The design, configuration, and arrangement of the ornaments in bas-relief, and mouldings, set forth in this specification and annexed drawings, forming a new and original design for the stove called the "Penn Radiator."

In testimony whereof, we have hereto signed our names before two subscribing witnesses.
